UNITED STATES PATENT OFFICE

158,215

PYROPHORIC LIGHTER

Wilbur P. Peterson and Richard Rupert,
Kansas City, Mo.

Application September 3, 1949, Serial No. 4,854

Term of patent 14 years

(Cl. D48—27)

To all whom it may concern:

Be it known that we, Wilbur P. Peterson and Richard Rupert, citizens of the United States, residing at Kansas City, in the county of Jackson and State of Missouri, have invented a new, original, and ornamental Design for Pyrophoric Lighter, of which the following is a specification, reference being had to the accompanying drawing, forming part thereof.

In the drawings:

Fig. 1 is a perspective view of a pyrophoric lighter showing our new design.

Fig. 2 is a side elevational view thereof.

Fig. 3 is an end view.

Fig. 4 is a view of the end opposite that shown in Fig. 3, and

Fig. 5 is a bottom view.

We claim:
The ornamental design for a pyrophoric lighter, as shown.

WILBUR P. PETERSON.
RICHARD RUPERT.
